SAVINGS BANK OR SIMILAR ARTICLE

Jack S. Geneser, Brownsville, Tex.

Application February 7, 1952, Serial No. 18,431

Term of patent 7 years

(Cl. D34—11)

To all whom it may concern:

Be it known that I, Jack S. Geneser, a citizen of the United States and a resident of the city of Brownsville, in the county of Cameron and State of Texas, have invented a new, original, and ornamental Design for a Savings Bank or Similar Article, of which the following is a specification, reference being had to the accompanying drawing, forming a part thereof.

On the drawing:

Figure 1 is a front perspective view of a savings bank, or similar article, showing my new design; and

Figure 2 is an elevational view thereof.

The back of the savings bank is conventionally plain.

I claim:

The ornamental design for a savings bank or similar article, as shown and described.

JACK S. GENESER.
